SIGNALING APPARATUS

John R. Moore, Tyler, Tex.

Application September 22, 1934, Serial No. 745,113

1 Claim. (Cl. 200—37)

This invention relates to an apparatus for producing periodic signals.

An object of the invention is the provision of an attachment for a clock which is formed of a plurality of readily replaceable units with means being provided for connecting one of the units directly with an operating shaft of a clock.

Another object of the invention is the provision of an apparatus for producing periodic signals in which a plurality of removable units are connected together for synchronous movement relative to the movements of any type of clock, the device being so constructed and arranged that it will produce similar and periodic signals each day of the week and which will prevent unnecessary signals at similar times during the day when not desired, means being employed for eliminating the reproduction of signals on certain days of the week.

20 A further object of the invention is the provision of an apparatus for producing periodic signals during the day and only on certain days of the week, the device being so constructed that certain signals of the group of signals to be produced 25 over a definite period may be selectively eliminated when desired.

This invention will be best understood from a consideration of the following detailed description, in view of the accompanying drawings forming a 30 part of the specification; nevertheless, it is to be understood that the invention is not confined to the disclosure, being susceptible of such changes and modifications as define no material departure from the salient features of the invention as 35 expressed in the appended claim.

In the drawings:

Figure 1 is a plan view of my signaling apparatus with the top of the casing removed,

Figure 2 is a side view in elevation of the device, 40 Figure 3 is a transverse vertical section taken along the line 3—3 of Figure 1,

Figure 4 is a fragmentary transverse vertical section taken along the line 4—4 of Figure 1,

Figure 5 is a fragmentary transverse vertical 45 section taken along the line 5—5 of Figure 1, and

Figure 6 shows more or less a diagram of the electric wiring.

Referring more particularly to the drawings, it will be seen that the casing 10 is provided for 50 housing not only a clock 11 but a plurality of removable units carried by frames 12 and 13. The clock may be of the usual spring type or is preferably of the electric alarm type. It will be noted that the units are movably connected to a revolving 55 shaft of the clock so that it will be unnecessary

to change or revise any of the mechanism connected with the clock.

Mounted in bearings in the frame 12 is a shaft 14 which is revolved by the clock in the direction indicated by the arrows in Fig. 2. This shaft is 5 connected to a revolving shaft 15 of the clock 11 by means of a removable connector generally designated by the numeral 16. The opposite ends of the shaft 14 project beyond the side walls of the frame 12, as shown at 17 and 18.

10 The connector consists of a sleeve 20 having an axial passage with a set screw 21 adapted to secure the sleeve to the shaft 14. An arm 22 projects from the sleeve 20 and has a flange 23 bolted to a disc or plate 24 which is formed of insulating 15 material. Arms 25 connect the disc or plate 24 with a sleeve 26 which is received by the end of the shaft 15 and secured to said end by means of a set screw 27.

A drum 30 is rigidly secured to the shaft 14 and 20 is located between the side walls of the frame 12 and disposed within said frame. A plurality of rings numbered respectively from 31 to 35 are secured in spaced relation to the outer face of the drum. Each of these rings is provided with 25 notches respectively indicated by the numerals 36 to 40, inclusive.

Each of the rings, as shown in Fig. 3, is provided with a second notch 36^a for a purpose which 30 will be presently explained. Each of the rings is provided with lines and numerals, thereby forming a dial. These lines divide the circumference of each ring into a number of degrees for indicating definite periods of time over an interval 35 of two hours.

The outer end 18 of the shaft 14 is also provided with a connector 41 similar to the connector 16 and this connector includes the insulating disc or plate 42 and the sleeves 43 and 44, the sleeve 43 being connected to one end of the shaft 14.

40 A plurality of arms, indicated by the numerals 45 to 49, inclusive, are pivotally mounted upon a shaft 50 which is carried by a bracket 51 secured to a cover plate 52 of the frame 12. Each arm is provided with an adjustable contact member 53 which is adapted to engage a contact member 54 when a finger 55 secured to an arm drops into one of the notches 36 or 36^a. The contact 54 is secured to a conductor 56 secured to 45 57 to the cover plate 52. A wire 58 is connected to the member 56 for a purpose which will be presently explained.

A drum 60 is secured to a shaft 61 mounted in bearings in the frame 13. A gear 62 is also secured to the shaft 61 and meshes with a spur 55

gear 63 secured to a shaft 64 also mounted in bearings in the frame 13. The outer end of the shaft 64 is secured to the sleeve 44 by means of a set screw 65. Thus it will be seen that the drum 5 60 is revolved in synchronism with the drum 30 but at a slower speed due to the variation in diameters between the gears 63 and 62.

The drum 60 is provided with segments of rings indicated by the numerals 66 to 70, inclusive. These segments are spaced at intervals 10 transversely of the drum. A complete ring 71 is secured to one end of the drum, as shown more particularly in Figure 2.

A plurality of spring-pressed arms, indicated 15 by the numerals 72 to 76, inclusive, are secured as shown at 77 to a plate 78 in such spaced relation that the respective arms will engage the segmental contacts 66 to 70, inclusive, and the respective arms are adapted to engage the contacts 20 once in every twenty-four hours since the proportions of the gears 63 to 62 are such that the drum 60 will be revolved only once in twenty-four hours.

A spring arm 80, secured at 81 to a connector 25 82 which operates as an electric wire, has a finger 81^a adapted to engage the ring contact 71 at all times.

A drum 83 is mounted on a shaft 84 and is revolved thereby. This shaft is revolved by a gear 30 85 which meshes with a gear 86 secured to the shaft 61. The diameter of the gears 86 and 85 are so proportioned that the drum 83 will make a complete revolution once in every seven days.

The drum is provided with a segmental ring 35 contact 87 which is adapted to be engaged by an electrical conducting spring arm 88 which is secured at 89 to one end of the conductor 82. The plates 52 and 78 may be formed of insulating material. The arm 88 is connected to the wire 82.

A complete ring contact 91 is secured to the 40 outer face of the drum 83 and is adapted to be engaged by a spring contact member 92 secured to the plate 78 and this spring contact member is connected by a wire 93 with one terminal 94 45 of a transformer 95. The other terminal of the transformer is connected by a wire 96 with signals 97 which may be in the form of electrically-operated bells, although other forms of signaling means may be employed for the purpose.

The drum 83 is shown more particularly in Figs. 50 2 and 5 and is provided with indicia at spaced intervals to indicate the days of the week.

The segmental ring contact 87 has a cut-out portion, as shown at 100, adjacent that portion 55 of the contact member which has the indicia Saturday and Sunday. In other words, where the device is not to be employed for producing signals on these days, the dropping of the spring arm 88 into the cut-out portion 100 will eliminate 60 signals on those special days.

The drum 30 forms the conductor and is connected by a wire 101 with the signals 97, as shown in Figure 6.

The operation of my device is as follows: The 65 apparatus is adapted to produce periodic signals and for this purpose may be used in a school for giving signals at stated times for indicating to the instructor and to the students the time for the opening of classes and the time for closing classes. In Fig. 3 the contact rings 31 and 32 70 are shown having numerals indicating definite periods of time, such as 8 o'clock, 8:10, 8:20, etc. The contact ring 32 may be provided with a variation of these numbers and may if desired 75 begin with the number "10" with the intervals

being completed in a period of two hours so that this second contact ring may represent the interval of time between 10 o'clock and 12 o'clock. Thus it will be seen that if classes are to begin at 8 o'clock on Monday morning the gravity-actuated arm 45 will cause the finger 55 to drop into the notch 36, when the clock has moved the drum to such position and the contact members 53 and 54 will be closed for the particular ring 31. The circuit then is completed through the 10 wire 58, the segmental contact 66, the spring arm 72, the current passing through the drum 60 to the continuous ring 71, the wire 82, through the spring arm 88 and segmental ring contact 87, through the drum 83, the continuous ring contact 15 91, the spring contact member 92, the wire 93, the transformer 95, and thence to the signal 97. The wire 101, as has been previously explained, is connected with the drum 30 and, therefore, with the contacts 31 to 35, inclusive. 20

If at any time it is desired to cut out any special time for producing the signals it is only necessary to move any one of the arms 45 to 49, inclusive, to the dotted line position shown in Fig. 3. 25

The segmental contacts 67 to 70, inclusive, on the drum 60 provide for closing the circuit as has been explained but prevents the signals from being repeated within twelve hours as ordinarily would occur at 8 o'clock in the evening if 30 such signals were produced at 8 o'clock in the morning. It requires a period of two hours for the drum 30 to complete a single revolution while it requires twenty-four hours for the drum 60 to complete a single revolution. Thus it will be 35 seen that the contacts 67 to 70, inclusive, close the circuit once in every twenty-four hours. The drum 83 maintains the circuit open for two days in the week, thereby eliminating Saturday and Sunday due to the cut-out portion 100 of the segmental ring contact 87. When the drum has been revolved to the point where the spring arm 88 drops into the cut-out portion 100, the spring arm is prevented by the plate 90 from touching the drum 83 thereby maintaining the circuit open. 45

It will be appreciated that while the notches on the ring contact 31 are located at 8 o'clock and 9:30 o'clock these notches may be located at different points to cause a signal to be produced at the time it is desired to start the 50 classes. Thus if the classes begin at 8:10 instead of 8:00 the notch could be placed opposite the indication 8:10 on the ring 31.

During the ordinary school period classes may start at 9 o'clock and last for an hour or an hour 55 and a half and the notches on the rings will be so positioned to produce the signal at the proper time. If during the summer period or at any other time it is desired to change the hours, the entire unit including the frame 12 may be removed from the casing 10 by the release of the set screws 21 and 43, as shown in Fig. 2, and another frame including the entire unit may be placed within the casing and readily attached to the shafts 14 and 64 as will be seen and the ring contacts 31 to 35, inclusive, may be provided with notches at the correct intervals to produce the signals at the times desired. If for any reason it may be necessary to revise the drum 60 or the drum 83 the entire unit including the frame 13 70 may be readily removed without disturbing any of the other parts. The device is attached directly to a revolving shaft of the clock without in any way changing any of the mechanism of the clock. 75

I claim:

In an apparatus for producing periodic signals, a casing provided with a top having an opening therein, a driven shaft in the casing, a drum secured to the shaft and having a portion projecting through said opening, a plurality of spaced rings secured to the surface of the drum and provided with notches, a lever for each ring and individually pivoted on the top and disposed in vertical alignment with the respective ring, each lever hav-

ing a free end thereof above the opening riding on a respective ring, means whereby said levers can be swung away from said rings and supported in an inoperative position on top of said case, a contact secured to the top beneath each lever, 5 a contact carried by each lever and adapted to engage the adjacently disposed contact on the top when the free end of a lever registers with a notch on a ring.

JOHN R. MOORE. 10
